UNITED STATES PATENT OFFICE.

MATTHEW F. BAYER, OF KENOSHA, WISCONSIN, ASSIGNOR TO SIMMONS COMPANY, OF KENOSHA, WISCONSIN, A CORPORATION OF DELAWARE.

BENDING MACHINE.

Application filed February 28, 1921. Serial No. 448,475.

To all whom it may concern:

Be it known that I, MATTHEW F. BAYER, a citizen of the United States, residing at Kenosha, in the county of Kenosha and State of Wisconsin, have invented certain new and useful Improvements in Bending Machines, of which the following is a specification.

This invention relates to bending machines but more particularly to such as are intended for the bending of metallic tubes.

The primary object of the invention is to provide a simple and efficient machine for accurately bending tubes to a predetermined curvature.

Another important object is to provide a machine which is capable of bending tubes into irregular or varying curvatures.

Further objects of the invention are to prevent scoring of the tube during the bending operation, to maintain uniformity of cross section of the tube during the bending operation, to provide a simple and efficient means for inserting a laminated core within the tube prior to the bending, to provide adjustable means for determining the extent of the insertion of the core within the tube, to prevent buckling of the strips composing the core during their insertion into the tube, to insure a firm pressure of the bending member upon the tube during the bending operation, and to provide simple and efficient actuating and controlling means for the bending member.

The many other objects and advantages of the invention will be better understood from the following specification when considered in connection with the accompanying drawings illustrating a selected embodiment thereof, in which:

Fig. 1 is a plan view of my invention;

Fig. 2 is a side elevation;

Fig. 3 is a section on the line 3—3 of Fig. 2;

Fig. 4 is an enlarged plan view of the binding head and adjacent parts;

Fig. 5 is a section on the line 5—5 of Fig. 4;

Fig. 6 is a section on the line 6—6 of Fig. 4;

Fig. 7 is a partial section on the line 7—7 of Fig. 4;

Fig. 8 is a section on the line 8—8 of Fig. 4;

Fig. 9 is a detail view illustrating the position of the core, tube, forming die and blade at the start of the core inserting operation;

Fig. 10 is the same as Fig. 9 but with the parts in the position of partial insertion of the core;

Fig. 11 is a detail view showing the end of the tube pressed against the positioning shoulders ready to receive the core;

Fig. 12 shows the tube at the completion of the bending operation, and

Fig. 13 is a detail view of the cross head and adjacent parts at the completion of the core inserting operation.

Referring to the drawings, the machine comprising the present invention is shown mounted upon a base or table 20 supported by legs 21. Fluid under pressure to actuate the various parts is contained in a supply tank 22 located in any suitable position and connected to the bending machine by a main pressure pipe 23.

A cylinder 24 has its outer end pivotally mounted on the vertical shaft 25 so that it is free to swing in a horizontal plane. A guide 24' has its ends secured upon the table and extends over the flat top 24'' at the inner end of the cylinder 24. Another cylinder 26 is stationary mounted upon the table 20. Pistons 27 and 28 operate in the cylinders 24 and 26, respectively. Fluid under pressure is admitted to the cylinder 24 in the rear of the piston 27 by the pipe 29. A pressure pipe 30 admits fluid to the front end of the cylinder 24. Flexible joints 29' and 31 are provided in the pipes 29 and 30, respectively, to permit the outer portion of these pipes to swing with the cylinder 24. The fluid pressure in the pipes 29 and 30 is controlled by the valve 32. Similarly, fluid under pressure is admitted to the cylinder 26 in rear of the piston 28 by the pipe 33 and to the front of this cylinder by the pipe 34. The fluid pressure in the pipes 33 and 34 is controlled by the valve 35.

The piston rod 36 connected to the piston 27 in the cylinder 24 carries on its inner extremity the bending head 37. The inner end 38 of the piston rod is forked and a pin 39 passes through the forked end. Toggle links 40 and 41 are connected to the pin 39. A boss 42 is formed on the link 41 and fits about the sliding sleeve 43. This boss 42 rests upon a corresponding boss 44 formed 10 in the sliding block 45 dovetailed in the saddle 46 of the head 37. The outer extremity of the toggle link 40 is forked and the pin 47 passes through the extremities thereof to unite this link to the link 48. The link 48 15 connects the upper extremities of the upright pins 49 and 50 which are mounted in the saddle 46. Rollers 51 and 52 are provided on the lower extremity of these pins 49 and 50, respectively, and are held in place 20 thereon by the heads 53 and 54. These pins 49 and 50 are locked within the saddle by the set-screws 55 and 56, respectively. A pin 57 fits within the sleeve 43 and is provided at its lower extremity with a roller 25 58 retained thereon by the head 59. The upper extremity of the pin 57 is connected to the operating handle 60 by the pin 61 fitting within the elongated slots 62 of the pin 57. The handle 60 is pivotally mounted on 30 the pin 63 in the slotted head 64 of the pin 39. A set-screw 65 may be provided in the forked end of the piston rod 36 to lock the pin 39 in position therein. An arm 67 is secured upon the boss 44 and extends upwardly beside the handle 60. The upper extremity of this arm 67 is perforated to receive a pin 68 to permit the handle 60 to be maintained in its raised position in the manner indicated in dot to support the bending 35 roller 58 in its inoperative position. An adjustable stop 37' is provided on the bending head 37 to limit the action of the toggle joint and thus prevent the locking of this head on the forming die 69.

40 The forming die 69 is secured upon the top face of the table 20 by screws 70 or other suitable means. This forming die preferably consists of a center block 71 secured between top and bottom plates 72 and 73 respectively. These top and bottom plates 72 and 73 project laterally beyond the side edge of the center block 71 to form with the face of the center block a forming groove 74 in the side face of the die to receive and 45 tightly fit the tube 75 which is to be bent. The form of this die will naturally depend upon the shape of the tube to be bent and the curvature of the bent tube. The top face of the upper plate 72 of the die forms 50 with the side face 80 of the center block a guide for the bending head 37 during the bending operation. The rollers 51 and 52 on the pins 49 and 50, respectively, engage the outer guide face 80 of the center block 55 71 and are positioned thereon by the slight-

ly projecting edges of the upper and lower plates 72 and 73. A flexible blade 81 has its inner extremity 82 secured to the cross-head 83 carried on the outer extremity of the piston rod 84 operated by the piston 85 in the cylinder 86. The cross-head 83 moves between suitable guides 83' on the base 20. Fluid under pressure is admitted to the cylinder 86 in the rear of the piston 85 by the pipe 87 controlled by the valve 88. The head 83 is withdrawn from its forward position by the spring 89 when the pressure in the cylinder 86 is released. A lock 90 controlled by the handle 91 is provided to secure the head in its advanced position.

A laminated core 92 composed of sufficient strips of thin steel or other suitable material to completely fill the interior of the tube, is inserted therein before the bending operation is commenced. The rear end 95 of the core 92 is secured to the upper end of the cross head 93. The forward end of the core fits within the perforation 95 in the block 96 which forms a stop to position the rear end of the tube 75. The lower extremity of the cross-head 93 is connected to the outer end of the piston rod 97. A cross-head guide 98 is mounted upon the table 20. A clamp 99 is preferably placed about the core about midway between its ends to prevent the buckling of the strips as the core is forced into the tube by the cross-head 93. The clamp 99 is attached to the table 20 by a chain 100. When a tube of short length is to be bent, a plate 101 of the proper length may be laid upon the guide 98, as indicated in dot in Fig. 2 of the drawings. This plate 101 will interrupt the movement of the clamp 99 with the core and cause this clamp to be slid rearwardly upon the core until it is engaged by the cross-head 93 in the manner shown in Fig. 13 of the drawings. By inserting a plate of the proper length in this manner the advance of the cross-head may be interrupted at any point in its travel, and thus limit the length of the core inserted within the tube. A fixed stop 102' abuts the end of the tube 75 to prevent longitudinal displacement of the tube during the insertion of the core. When a short length of tube is to be bent, an arm 102 pivoted at 103 is provided. This arm 102 has a head 104 formed on its outer extremity so that when the arm is swung into the position indicated in dot in Fig. 1, the end face 104' forms a stop for the tube in the same manner as the fixed stop 102' in the case of a full length tube. The length of the arm 102 would naturally be varied for different lengths of tube. Any other suitable form of adjustable stop might be substituted therefor.

In the operation of the device the tube is inserted into the die in the position indi-

cated in solid lines in Fig. 9 of the drawings, with the inner end of the tube against the stop block 96 and the outer end against the stop 102, the blade 81 being in the withdrawn position as indicated in this figure. The blade 81 is now forced against the tube by the cross-head 93 to retain the inner end of the tube in the forming groove, as indicated in Figs. 7 and 10. The core 92 is next forced into the tube by the cross-head 93 when fluid under pressure is admitted to the cylinder 26 through the pipe 33 by the operation of the valve 35 in the proper direction. The handle 60 is now depressed to bring the roller 58 into its operative position opposite the blade 81.

Pressure is now admitted to the cylinder 24 in rear of the piston 27 which advances the piston rod 36 carrying the bending head 37. The advance of the piston rod 36 acts upon the toggle links 40 and 41 to cause the rollers 50 and 51 to press against the rear guide face of the die, and the roller 58 to be drawn inwardly and to tightly press the blade 81 against the outer face of the tube. The further advance of the piston rod causes the bending head to move outwardly along the die 69 and to force the tube into the forming groove therein. The cylinder 24 swings upon its pivoted rear end and is free to move in the path determined by the die. The blade 81 bends with the tube under the pressure of the roller 58 and prevents any scoring of the outer face of the tube by this roller during the bending operation. The bending head is now returned to its initial position by reversing the valve 32. The blade 81 may now be withdrawn by disengaging the lock 86 and releasing the pressure in the cylinder 90.

The core may be withdrawn from the tube upon the completion of the bending operation by reversing the valve 35 to admit pressure through the pipe 34 and thus force the cross-head 93 rearwardly to the position indicated in Fig. 2. The bent tube may now be removed from the bending die and the operation repeated on a new tube. The same core may be used in bending a large number of tubes.

It will thus be seen that with the present invention a tube may be bent into substantially any curvature by the use of the proper die and the tube is fully protected against scoring during the bending operation. The toggle connection between the actuating piston and the bending head insures complete and accurate bending of the tube. The core is quickly and easily inserted into and withdrawn from the tube and the same core may be used indefinitely. The bending operation is entirely mechanical and requires no skill on the part of the operator. The amount of the insertion of

the core in the tube is readily adjusted. The core provides uniformity in cross section of the bent tube.

I am aware that many changes may be made in the form and arrangement of parts without departing from the spirit of my invention, and I reserve the right to make all such as fairly fall within the terms of the following claims.

I claim:

1. In a machine for bending attenuated members, a former, a guiding member, a bending member straddling the former and said guiding member, an actuating member for moving the bending member along the former, and a pivotal connection between said bending member and said actuating member, for permitting rocking of the bending member relative to the actuator. 75

2. In a machine of the class described, a curved forming member, a correspondingly curved guide, a bending head co-operating with said guide for bending an attenuated member around said forming member, and an actuator for moving said head along said guide and said forming member, said actuator being pivotally connected to said head to permit rocking of said head relative to said actuator. 85

3. In a machine of the class described, a curved forming member, a correspondingly curved guide, a bending head co-operating with said guide for bending an attenuated member around said forming member, and a reciprocating actuator pivotally connected to said head for moving said head along said guide and said forming member. 95

4. In a machine of the class described, a support, a cylinder mounted upon said support and movable relative thereto, a piston within said cylinder, a piston rod connected to said piston, a former, and means for actuating said piston to move said head over the operative face of said former, a bending head carried upon said rod, a guide for said head. 105

5. In a machine of the class described, a support, a cylinder pivotally mounted on said support, a piston within said cylinder, a piston rod connected to said piston, a bending head mounted upon said piston rod, a guide for said head, a die including a forming groove and means for admitting fluid under pressure to said cylinder to cause said head to be moved longitudinally of said groove and to be forced toward said die. 115

6. In a machine of the class described, a support, a cylinder pivotally mounted at one end upon said support, guiding means for said cylinder, a piston within said cylinder, a piston rod, and a bending head supported by said rod and connected thereto by a toggle joint. 125

7. In a bending machine, a die provided 130

- with a forming groove, a presser member disposed opposite to the face of said die and movable longitudinally of said groove, an actuator for said head pivotally connected thereto, and a tube protecting member interposed between said die and said presser member, the movement of said presser member being independent of said protecting member.
- 10 8. In a bending machine, a die provided with a forming groove, a presser member disposed opposite to the face of said die and movable longitudinally of said groove, an actuator for said head pivotally connected thereto, and a flexible metallic strip interposed between said die and said presser member and extending substantially longitudinally of said groove, said presser member passing over the face of said strip during said longitudinal movement.
- 15 9. In a bending machine, a die provided with a forming groove, a presser member disposed opposite to the face of said die and movable longitudinally of said groove, a flexible member interposed between said die and said presser member and means for moving said flexible member toward and from said die including a cylinder, a piston in said cylinder, a piston rod, a cross-head on said rod connected to said flexible member, and means for admitting fluid to said cylinder to actuate said piston.
- 20 10. In a bending machine, a die provided with a forming groove, a presser member disposed opposite to the face of said die and movable longitudinally of said groove, a flexible member interposed between said die and said presser member and means for moving said flexible member toward and from said die including a cylinder, a piston in said cylinder, a piston rod, a cross-head on said rod connected to said flexible member, and means for admitting fluid to said cylinder to actuate said piston.
- 25 11. In a tube bending machine, the combination with a laminated core of means for inserting a laminated core into a tube to form a filler therefor, and means for bending the filled tube comprising a forming member, a presser member movable relative to said forming member and guided thereby, and means for actuating said presser member.
- 30 12. In a tube bending machine, the combination with a laminated core of means for inserting said core into the tube to form a filler therefor, and means for bending the filled tube comprising a die provided with a forming groove, a bending member movable over the face of said die longitudinally of said groove and guided by said die means for actuating said bending member, and means for controlling said actuating means.
- 35 13. In a machine of the class described, the combination with a laminated core of means for inserting the core into a tube comprising a cylinder, a piston within said cylinder, a piston rod, a cross-head on the outer extremity of said rod, core engaging means on said cross-head, and means for admitting fluid under pressure to said cylinder to actuate said piston.
- 40 14. In a machine of the class described, the combination with a laminated core of means for inserting the core into a tube before bending said tube and withdrawing said core from said tube upon the completion of the bending operation comprising a cylinder, a piston within said cylinder, a piston rod connected to said piston, a cross-head mounted on said rod, guiding means for said cross-head, means on said cross-head for engaging said core, and means for admitting fluid under pressure to said cylinder to actuate said piston.
- 45 15. In a bending machine, a forming die and a bending head movable relative to said die and comprising a saddle, a slide mounted in said saddle, a tube bending member carried by said slide, and a toggle joint connecting said slide and said saddle for moving said slide relative to said saddle.
- 50 16. In a bending machine, a forming die and a bending head bodily movable relative to said die and comprising a saddle, a guide, guide engaging means on said saddle, a slide mounted in said saddle and movable therein substantially toward and from said engaging means, a tube bending member carried by said slide, and a toggle joint connecting said saddle and said slide for actuating said slide.
- 55 17. In a bending machine, a bending head comprising a saddle, a guide, guide engaging rollers on said saddle, a slide mounted in said saddle and movable therein substantially toward and from said rollers, a tube bending member carried by said slide and movable relative thereto into and out of operative position, and a toggle joint connecting said slide and said saddle for actuating said slide.
- 60 18. In a machine of the class described, a laminated core, and means for inserting said core into a tube comprising a plunger, core engaging means on said plunger, means for actuating said plunger, and adjustable means for limiting the forward stroke of said plunger.
- 65 19. In a machine of the class described, a curved forming member, a correspondingly curved guide, a bending head cooperating with said guide for bending an attenuated member around said forming member, and a reciprocating actuator pivotally connected to said head for moving said head along said guide and said forming member, said actuator being capable of a limited oscillation as it reciprocates.

20. In a tube bending machine, a stationary die provided with a forming groove, a bending head movable longitudinally of said groove and co-acting with opposing 5 faces of said die to press a tube into said groove as said head is advanced, and means including a pressure cylinder for actuating said head.

21. In a bending machine, a die provided 10 with a forming groove, a bending head movable upon the face of said die longitudinally of said groove, and means for actuating said head including a plunger, and a toggle joint connecting said plunger with 15 said head.

22. In a machine of the class described, 20 a base, a curved forming member, a correspondingly curved guide, a bending head co-operating with said guide for bending an attenuated member around said forming member, and a two-part actuator for moving said head relative to said base, one of

the parts of said actuator being pivotally connected to the base and the other pivotally connected to the head. 25

23. In a machine of the class described, a forming member, a bending member, one of said members being adapted to travel over the operative face of the other member, means for effecting said travel, and guides 30 along the path of said travel for directing the same, and, during such travel, maintaining a fixed relation between said bending member and the surface of the former. 35

24. In a bending machine, presser mechanism including a cylinder, a piston in said cylinder, a piston rod connected to said piston, a presser head mounted on said rod, and acting at substantially a right angle to the axis thereof, and means for admitting fluid 40 under pressure to said cylinder to actuate said piston. 45

MATTHEW F. BAYER.
